his attorney.

UNITED STATES PATENT OFFICE.

EMIL GRUENFELDT, OF CLEVELAND, OHIO, ASSIGNOR TO THE BAKER MOTOR VEHICLE COMPANY, OF CLEVELAND, OHIO, A CORPORATION OF OHIO.

ADJUSTABLE STEERING-MAST SUPPORT.

No. 905,175.

Specification of Letters Patent.

Patented Dec. 1, 1908.

Application filed November 15, 1907. Serial No. 402,331.

To all whom it may concern:

Be it known that I, EMIL GRUENFELDT, a subject of the Emperor of Germany, resident of Cleveland, county of Cuyahoga, and State of Ohio, have invented a new and useful Improvement in Adjustable Steering-Mast Supports, of which the following is a specification, the principle of the invention being herein explained and the best mode in which 10 I have contemplated applying that principle, so as to distinguish it from other inventions.

My invention relates to steering mast supporting devices for motor vehicles and particularly to that class of such devices which is adapted for use in electrically propelled pleasure vehicles in which the steering mast is usually mounted upon the outside of the vehicle-body.

20 The object of the invention is to provide supporting means for the mast which may be readily adjusted so as to bring the two bearings into perfect alinement.

The said invention consists of means hereinafter fully described and particularly set forth in the claims.

30 The annexed drawing and the following description set forth in detail, certain mechanism embodying the invention, the disclosed means constituting but one of various mechanical forms in which the principle of the invention may be applied.

In said annexed drawing:—Figure I represents a side elevation of the motor vehicle body showing my invention applied thereto. Fig. II represents a cross-sectional view of the motor vehicle frame, upon an enlarged scale, showing the lower and adjustable steering mast bracket secured thereto, a portion of the steering mast being shown 40 in the bearing of such bracket. Fig. III represents a side elevation of the lower and adjustable bracket, on the same scale as it is illustrated in Fig. II.

45 The upper portion of the steering mast A is mounted in a bracket B of the usual construction in which a vertical bearing is formed for allowing the mast to turn therein. This bracket is secured to the body, usually 50 immediately below the seat and projects laterally of the body a suitable distance. The lower end of the mast is mounted in the lower bracket C, Figs. II and III. This bracket consists of two main members c 55 and c', member c being provided with an

angle member c² which is adapted to fit upon and be secured, by means of suitable rivets or bolts, to the frame D of the vehicle. This member c projects downwardly and laterally so as to bring the member c' substantially 60 beneath the bottom plane of the bracket B. The said member c is bifurcated, as shown, and these bifurcations are provided with horizontally alined and elongated slots c³. The member c' is formed with two lateral bosses c⁴ c⁴ which are formed with horizontally threaded bores c⁵ c⁵. These bosses fit between the bifurcations and machine-screws c⁶ c⁶ pass through the slots and are screwed into the threaded bores c⁵ c⁵, as 70 shown. The member c' is further formed with a vertical smooth bore forming the bearing for the steering mast, and a collar a is secured to the mast and rests upon the member c'. This collar prevents the mast 75 from dropping through the bearings, as will be readily understood.

In order to obtain the proper alinement of the bearings in the bracket B and in the member C, the screws c⁶ c⁶ are loosened and 80 member c' moved laterally so as to change the position of the screws in the slots c³ until the axial line of the bearing in bracket B passes through the center of the bearing in member c'. The latter is then oscillated 85 until the axial line of its bearing coincides with that of the bearing in bracket B. The above method of adjustment is best carried out by passing the steering mast down through the bracket B until its lower extremity is adjacent to the member c' of the lower bracket. This member is then oscillated and adjusted laterally until the lower extremity of the mast may be passed into and through the bearing. This operation 90 having been completed the screws are then turned to fix the member c' in the position thus obtained.

Other modes of applying the principle of my invention may be employed, instead of the one explained, and change may be made as regards the mechanism herein disclosed, provided the means covered by any one of the following claims be employed.

I, therefore, particularly point out and 105 distinctly claim as my invention:—
1. In mechanism of the class described, the combination with an upper steering-mast bracket, of a lower bracket comprising a member fixed to the vehicle frame, and a 110

member forming a bearing for the mast, such latter member being adjustable upon an axis substantially parallel with the plane of said frame and being further adjustable in 5 a plane substantially parallel with such frame-plane.

2. A steering mast bracket for motor vehicles comprising a member adapted to be fixed to the vehicle, a member mounted pivotally in the first mentioned member and adjustable in a lateral direction, and means for fixing such pivotally mounted member upon its axis.

3. A steering-mast bracket comprising a member adapted to be fixed to the vehicle frame and formed with a slotted portion, a member forming a bearing for the mast, and pivotal means upon which said bearing

member is mounted, said latter means being adjustably securable in said slotted portion 20 of the fixed member.

4. A steering-mast bracket comprising a member adapted to be fixed to the vehicle frame and formed with two slotted bifurcations, a member forming a bearing for the 25 mast, and two axially aligned screws passing through the slots in said bifurcations and having screw-threaded engagement with said bearing member.

Signed by me, this 12th day of November, 30 1907.

EMIL GRUENFELDT.
